UNITED STATES PATENT OFFICE.

HERBERT F. SCATCHARD, OF DARBY, PENNSYLVANIA, ASSIGNOR OF ONE-HALF TO
JOHN S. LATTA, OF PHILADELPHIA, PENNSYLVANIA.

SWITCH-OPERATING DEVICE.

981,886.

Specification of Letters Patent. Patented Jan. 17, 1911.

Application filed November 12, 1910. Serial No. 591,977.

To all whom it may concern:

Be it known that I, HERBERT F. SCATCHARD, a citizen of the United States, residing at Darby, in the county of Delaware, State 5 of Pennsylvania, have invented a new and useful Switch-Operating Device, of which the following is a specification.

My invention consists of an improved switch-operating device for electric or other 10 railway in which a switch may be thrown from a trolley or other car or a locomotive while the latter is in motion.

It further consists of other novel features of construction, all as will be hereinafter 15 fully set forth.

For the purpose of illustrating my invention I have shown in the accompanying drawing one form thereof which is at present preferred by me, since the same has 20 been found in practice to give satisfactory and reliable results although it is to be understood that the various instrumentalities of which my invention consists can be variously arranged and organized and that my 25 invention is not limited to the precise arrangement and organization of these instrumentalities as herein shown and described.

Figure 1 represents a top-plan view of as much of a railway track and switch as will 30 illustrate my invention. Fig. 2 represents a side elevation of a portion of a rail (partly broken away) and of the actuating device on the car and the actuated device on the road-bed,—the car floor or platform appearing 35 in section,—illustrating the actuating device in operative position. Fig. 3 represents a detail view of the actuated device at the side of the rail, said latter being shown in transverse section. Fig. 4 represents a 40 detail view of a part of the transmission mechanism. Fig. 5 represents a plan view on a larger scale, of the switch-throwing mechanism. Fig. 6 represents a section of a car floor or platform and a side elevation of 45 a hand-operated form of my actuating device. Fig. 7 represents a plan view of a portion of a track and switch provided with my switch-throwing apparatus, illustrating 50 the same applied to a switch connecting to a side track turning to the opposite side of the side track illustrated in Fig. 1.

Similar numerals of reference indicate corresponding parts in the figures.

Referring to the drawings: 1—1 designates the main track rails, 2—2, the side

track rails, 3 indicates the movable switch-tongue, and 4 indicates the frog. At the inner side of one of the rails and at a suitable distance from the switch, a cushion-block, 5, substantially T-shaped, is supported upon springs, 6, beneath the arms of its head. Said cushion-block is pivoted upon the end of a lever, 7, which is fulcrumed to rock in a vertical plane, transverse to the track. The other end of this lever engages 65 a downwardly pointing fork, 8, upon one arm of a bell-crank, 9, suitably pivoted in the road-bed. The other arm of this bell-crank is connected by a link or rod, 10, to one arm of a lever, 11, fulcrumed to rock in a horizontal plane, and the other arm of said lever is connected by a rod, 12, to one arm of a horizontally fulcrumed lever 13. A cog-wheel, 14, is journaled to rotate in a horizontal plane, and meshes with a pinion, 75 15, having a wrist-pin, 16, upon its face, to which pin a link, 17, is pivoted, which again is pivotally connected to a rod 18, said rod being secured to an ear 37 upon the switch-tongue. A ratchet-wheel, 19, is concentric 80 with and secured upon the cog-wheel, and its teeth are engaged by a pawl, 20, upon a sliding bar, 21, which is pivotally connected to the horizontally movable lever 13. The ratchet teeth and the cog-wheel and pinion 85 are so proportioned that the movement of the ratchet wheel for the space of one tooth will give the pinion one half a revolution so that by its link connection to the switch-tongue the latter will be thrown from one 90 position to another.

Beneath the floor or platform, 22, of the car or locomotive is secured a vertical tubular guide, 23, in which a plunger, 24, slides, and a roller, 25, is journaled in the lower 95 end of said plunger so as to engage the cushion block 5, along side the rail when the plunger is depressed. One arm of a bell-crank, 26, is pivotally connected to the plunger, and said bell-crank is fulcrumed beneath the floor or platform. A piston-rod, 27, is pivotally connected to the other arm of the bell crank, and this rod is connected to a piston, 28, in a cylinder, 29, and having a spring, 30, for returning it. A pipe, 31, is connected to the end of the cylinder to convey air, steam or other fluid under pressure to the same, and the flow through this pipe is controlled by a suitable three-way or other valve, 32, upon the car or locomotive. 105 110

In Fig. 6 is illustrated a device for operating the actuating device by hand power, and the air-cylinder, spring, piston and piston-rod serve in this case merely as a retracting device. The plunger and roller are depressed by a rod, 33, pivoted at one end to the arm of the bell-crank 26, opposed to the piston-rod, and the other end of said rod is pivoted to a hand-lever, 34, provided with a 10 spring-latch, 35, engaging a quadrant-rack, 36. By pulling back on the lever, the plunger is depressed, and the spring will raise the same when the lever is released.

In the switch illustrated in Fig. 7, the 15 side-track is illustrated as leading to the left instead of to the right, as illustrated in Fig. 1, and the pinion 17 is consequently arranged at a point diametrically opposite its location in Fig. 1, so as to be on the side 20 where the switch-tongue is located. The operation of this switch is identical with that of the switch illustrated in Fig. 1.

When a locomotive or car which will hereafter be referred to as the "car" arrives 25 near the switch and it is desired to throw the same, the valve upon the car is actuated to admit air or whatever motive fluid is used to the cylinder, back of the piston, pushing the latter and the piston-rod forward to 30 rock the bell-crank and depress the plunger to bring the roller upon the same in position to depress the cushion-block when the roller passes over the same, or if the hand-lever is employed, the lever is pulled, accomplishing 35 the same result. The depression of the cushion-block rocks its lever, which again actuates the bell-crank, the connecting-rods and the levers to move the sliding bar and pawl to rotate the ratchet-wheel, and cog- 40 wheel for the space of one ratchet-tooth. The cog-wheel and pinion are so proportioned that the rotation of said wheel for the space of one ratchet-tooth will give the pinion one half revolution, and the switch- 45 tongue will thus be thrown from one extreme to the other of its movement, so that the main track or side track will be opened according to which track was closed by the last preceding actuation of the switch. As 50 soon as the switch has been thrown, the air is turned off and exhausted from the air-cylinder or the hand-lever is released, whereupon the plunger rises and is clear from the track. As soon as the pressure of the roller 55 is released from the cushion-block, the springs raise the same, thereby drawing the pawl-carrying bar back so as to be ready to engage another ratchet tooth.

By this apparatus a switch can be thrown 60 from a train or car by the engineer or motorman, without the necessity for a member of the crew leaving the train or car and without the necessity for a switchman being located at the switch. All parts of the 65 switch-operating mechanism can be placed

beneath or level with the road-bed and be suitably incased, and the parts upon the locomotive or car are few and simple and do not occupy much space. Where air or steam or other motive fluid is not practically accessible, suitable mechanical means for operating the actuating plunger by hand or foot power or by other accessible power may be provided on the engine or car, one such form,—operation by hand-power,—being 70 illustrated in Fig. 7. By proper proportioning of the throw of the pawl-carrying bar, the ratchet-wheel, the cog-wheel and the pinion, the exact movement necessary for the throwing of the switch may be provided 75 for, so that the actuation of the switch-operating mechanism will be positive and accurate without danger of the switch throwing back to its first position, as the actuation of the cushion-block of such mechanism is 80 just sufficient to cause the one movement of the latter and then all parts return to normal and inactive position.

Having thus described my invention, what I claim as new and desire to secure by Letters Patent, is:—

1. In a device of the character stated, a cushion-block adjacent the track, a switch-tongue, a pinion having a wrist-pin upon its face, a link pivoted to said wrist-pin and to the switch-tongue, a cog-wheel meshing with said pinion, a ratchet-wheel connected to rotate said cog-wheel, a sliding bar carrying a pawl engaging the ratchet-wheel, and connecting means between said sliding bar and cushion block to reciprocate the bar when the cushion block is depressed.

2. In a device of the character stated, a cushion-block adjacent the track, a switch-tongue, a pinion having a wrist-pin upon its face, a link pivoted to said wrist-pin and to the switch-tongue, a cog-wheel meshing with said pinion, and means connected to the cushion-block and cog-wheel to partly rotate the latter when the former is depressed.

3. In a device of the character stated, a switch-tongue, a ratchet wheel, a sliding bar carrying a pawl engaging said wheel, means for reciprocating said bar and constructed to be actuated from a passing car, a pinion carrying a wrist-pin, a link pivoted to said pin and to the switch tongue, and gear connection between said pinion and the ratchet wheel whereby the former is given one half revolution from the movement of the latter by each movement in one direction of the sliding bar and pawl.

4. In a device of the character stated, a switch, a ratchet-wheel, a sliding bar carrying a pawl engaging said wheel, means for reciprocating said bar and constructed to be actuated from a passing car, a pinion carrying a wrist-pin, a link pivoted to said pin and to the tongue of the switch, and a cog-wheel connected to rotate with the ratchet-

wheel and engaging the pinion, said pinion, cog-wheel and ratchet-wheel being so proportioned that the pinion is given one half revolution by each movement in one 5 direction of the sliding bar and pawl.

5. In a device of the character stated, a cushion-block adjacent a rail of the track and substantially T-shaped, springs beneath the ends of the T-head of the same, a vertically 10 movable lever having one arm pivoted to the cushion-block, a bell-crank fulcrumed to rock in a vertical plane and having one arm pivotally connected to said lever, a horizontally movable lever, a link 15 between an arm of said lever and the other

arm of the bell-crank, a horizontally movable lever, a rod connecting one arm of said lever with an arm of said before-recited horizontal lever, a sliding bar pivotally connected to the second horizontal lever, a pawl 20 on said bar, a ratchet-wheel engaged by said pawl, a switch tongue, and mechanism between said ratchet-wheel and switch-tongue for throwing the latter by the rotation of the former.
